UNITED STATES PATENT OFFICE.

WARD S. IRELAND, OF ST. LOUIS, MISSOURI, ASSIGNOR, BY MESNE ASSIGNMENTS, TO THE DAVIS SEWING MACHINE COMPANY, A CORPORATION OF DELAWARE.

DRAIN BOARD FOR CLOTHES WRINGERS.

1,425,099.

Specification of Letters Patent. Patented Aug. 8, 1922.

Application filed October 27, 1919. Serial No. 333,599.

To all whom it may concern:

Be it known that I, WARD S. IRELAND, a citizen of the United States of America, a resident of St. Louis, in the State of Missouri, have invented certain new and useful Improvements in Drain Boards for Clothes Wringers, of which the following is a full, clear, and exact description, reference being had to the accompanying drawings, forming a part of this specification.

My invention relates to a drain board for application to clothes wringers, and has for its object the provision of a drain board so constructed as to permit of attachment to and detachment from a clothes wringer to conduct the water squeezed from clothes by the wringer rolls to a point more remote from the wringer than is permitted by the use of the drain boards commonly present in clothes wringers. The drain board to which my present invention relates is one intended more particularly for use in conjunction with the main drain boards as commonly found in clothes wringers, and forms an extension or supplemental board leading from the main drain board, provision being made for instant application and removal of the supplemental drain board.

Fig. I is an elevation of the upper portion of a power washing machine and a swinging wringer supported thereby with my supplemental drain board attached to said wringer.

Fig. II is a longitudinal section through the main drain board of a wringer and my supplemental drain board fitted thereto.

Fig. III is a top plan view of my supplemental drain board.

In the drawings A designates a clothes wringer rotatably supported by a washing machine frame B, so that said wringer may be swung into various positions for use. The wringer A includes a main drain board C located beneath the wringer rolls and preferably so mounted as to permit of its being tilted to conduct water to either side of the wringer. In the bottom of the drain board C, preferably near its front and rear edges, are longitudinal grooves c.

My supplemental drain board, designated as a whole by the character D, is preferably made of sheet metal and is provided with side tongues 1 extending upwardly from the side edges of the board and terminating in inturned lips, spaced from the body of the

board. Said tongues are adapted to embrace the marginal ends of the main drain board C so that their lips overhang said main drain board, with the result of restraining the supplemental board from lateral and vertical movements relative to said main drain board. At the rear end of the supplemental board is an upturned transverse lip 2, preferably curved to avoid the presence of an upstanding sharp edge. This lip is adapted to enter either of the longitudinal grooves c in the main drain board when the supplemental board is applied thereto, and thereby serves as a detent to prevent slippage of the supplemental drain board in a forward or rearward direction relative to said board and the wringer in which it is mounted.

It will be apparent that the supplemental board D may be slipped onto the main drain board at either side of the wringer, according to the direction in which the main drain board is tilted, and that it will engage and be held from movement relative to said main drain board by the simple act of slipping it thereonto, so that the side tongues 1 will embrace the main drain board and the upturned lip 2 will enter into one of the grooves c in the main drain board, the extended forward end of the supplemental board serving by its gravitating tendency to retain the upturned lip in the groove into which it has been seated.

When the supplemental drain board D is slipped onto the left side of the main drain board C, as shown by Fig. II, said supplemental board D will extend from the left side of the main board C, and the supplemental board is then secured by means of its yielding lip 2 which enters the groove c at the right side of the main drain board C. However, if the supplemental drain board D is slipped onto the right hand side of the main drain board C (Fig. II), the yielding lip 2 will enter the groove c at the left side of the main drain board, and the supplemental board will then extend from the right hand side of the main drain board C. It will therefore be understood that the supplemental drain board D is adapted to be slipped onto both sides of the main drain board C, so as to extend from either of said sides, and when in either position the board D is secured by its lip 2 which is adapted to extend into either groove c.

The side edges of the supplemental board

are preferably upturned at 3 to prevent the water descending on the supplemental board from flowing over said edges, and said board is also preferably provided with ribs 4 serving to stiffen and strengthen it, thereby making it possible to utilize thinner sheet metal for the production of said board than would otherwise be feasible.

My drain board may also be used in conjunction with the clothes wringer A without attaching it to the main drain board of the wringer. A rib or depression 2', extending across the supplemental drain board is adapted to engage the bottom member of the wringer, and by positioning the drain board on the top of the washing machine when the wringer is offset from the board supporting portion of the machine, the drain board will conduct water to a desired point of delivery.

I claim:

1. The combination with a wringer having a main drain board, of a supplemental drain board adapted to be slipped onto either side of said main drain board so as to extend from either of said sides, and fastening means whereby said supplemental drain board may be secured at either of said sides.

2. The combination with a wringer having a main drain board, of a supplemental drain board adapted to be slipped onto either side of said main drain board so as to extend from either of said sides, and fastening means whereby said supplemental drain board may be secured at either of said sides, said fastening means being formed integral with the respective drain boards.

3. The combination with a wringer having a main drain board, of a supplemental drain board adapted to be slipped onto either side of said main drain board so as to extend from either of said sides, and fastening means whereby said supplemental drain board may be secured at either of said sides, said fastening means including a yielding

detent formed integral with said supplemental drain board and cooperating with said main drain board to prevent slippage of said supplemental drain board.

4. The combination with a wringer having a main drain board, of a supplemental drain board adapted to be slipped onto either side of said main drain board so as to extend from either of said sides, the bottom of said main drain board being provided with grooves near its front and rear edges, and one end portion of said supplemental drain board being provided with a yielding detent adapted to enter either of said grooves so as to secure said supplemental drain board at either side of said main drain board.

5. The combination with a wringer having a main drain board, of a supplemental drain board adapted to be slipped onto either side of said main drain board so as to extend from either of said sides, said supplemental drain board being located below said main drain board and provided with side tongues which extend over and engage the top of said main drain board, the bottom of said main drain board being provided with grooves near its front and rear edges, and one end of said supplemental drain board being provided with a yielding detent adapted to extend into either of said grooves so as to cooperate with said tongues in securing the supplemental drain board at either side of said main drain board.

6. The combination with a wringer having a main drain board, of a supplemental drain board made of sheet metal having side tongues adapted to embrace said main drain board and a yielding lip formed integral with said supplemental board and engaging the bottom of the main board to prevent slippage of said supplemental board.

In testimony that I claim the foregoing I hereunto affix my signature.

WARD S. IRELAND.
